UNITED STATES PATENT OFFICE

2,417,578

HINGED ROAD MAT

William E. White, Bethlehem, Pa., assignor to
Bethlehem Steel Company, a corporation of
Pennsylvania

Application April 7, 1945, Serial No. 587,055

7 Claims. (Cl. 72—109)

1

This invention relates to a reinforcing mat for concrete roadways which is hinged so that the parts may be folded upon each other.

One of the objects of this invention is to make a road mat which will require less shipping space thus permitting shipment where clearance problems would prohibit the delivery of mats of rigid construction for full roadway widths.

Another object of this invention is to provide a road mat which may be delivered in a compact form and yet when placed in position in the roadway and opened up for use requires no additional fastening means to hold the parts in position.

Still another object of this invention is to provide a road mat which, when the various members composing the mat are assembled and fastened in place, can be folded for shipment and upon arrival at the roadway site opened up for use without any difficult assembly, and yet will have no tendency for the parts to become accidentally unhooked or disconnected during the pouring of the concrete slab.

These and other objects are attained by means of a structure which is simple of manufacture and which requires no additional material to provide the hinged joint.

In the accompanying drawings:

Figure 1 shows a plan view of a road mat with a hinge that permits the halves of the mat to be folded upon each other.

Figure 2 shows an enlarged view of one of the transverse rod ends forming one of the hinge elements.

Figure 3 is a view similar to Figure 2 in which the transverse rods from both halves of the mat form hinge elements.

Figure 4 is a section through the pivotal axis of the hinge.

Referring to the drawings more in detail, 10 and 11 are the units or leaves comprising the mat, 10 being comprised of the longitudinal rods 12 and the transverse rods 13 while 11 is comprised of the longitudinal rods 12 and 14 and the transverse rods 15. The rods may be fastened at their intersections by means of clips 16 or by welding, either method being well known in manufacturing reticular structures for reinforcing purposes. In Figure 1, the rods 15 are shown with straight ends and extend somewhat beyond the longitudinal rod 14 which serves as the pivotal axis of the hinge. After the unit 11 has been assembled the rods 12 are placed in proper position and the rods 13, each of which has a spiral end 17 of a "pig-tail" nature which hooks over or under

2

the pivotal axis, are placed in position. This is accomplished by starting with the rod in an inclined position as indicated by dotted lines, entering the pivotal axis rod into the pitch opening of the spiral and swinging the rod 13 into its final position at right angles to the axis, so that the diameter of the "pig-tail" registers with the diameter of the pivotal rod. When the rods 13 are fastened to the rods 12 at their various intersections they cannot be disengaged from the axis rod due to the peculiar shape of the spiral ends, but rotary motion is possible about the rod 14 thus permitting unit 10 to be folded over upon unit 11.

15 In Figure 2, one of the hinge elements is shown indicating more clearly the type of spiral ends 17 on the rods 13. This spiral end consists of one turn of the rod, the spiral having a pitch of somewhat greater magnitude than the diameter 20 of the axis rod 14 to permit the assembly of the hinge element. A suitable type of clip 16 for fastening rod 15 in place is also indicated, it should, however, be noted that a weld may be used for this fastening instead of a clip. Figure 25 3 shows a modification of the hinge element in which spiral hooks 17 are used on the ends of the transverse rods of both units, the rods 13', similar to rods 13, replacing rods 15.

While I have shown my invention in but two 30 forms, it will be obvious to those skilled in the art that it is not so limited, but is susceptible of various changes and modifications without departing from the spirit thereof and I desire, therefore, that only such limitations shall be 35 placed thereupon as are imposed by the prior art or as are specifically set forth in the appended claims.

Having thus described my invention, what I claim as new and desire to secure by Letters

40 Patent is:

1. A hinged reinforcing mat comprising two reticular units each comprised by a series of rods attached to each other, a plurality of rods of one unit each terminating in a helix turned at right angles to the rod to form a hinge when combined with a rod of the other unit to serve as an axis capable of permitting a relative substantial folding movement between the two units.

2. A hinged reinforcing mat comprising two 50 series of rods placed at an angle to each other to form a reticular structure, the continuity of the first series of rods being broken near one of the second series of rods and the ends of certain rods of the first series having a helical loop of approximately 360° turned on the end of each at

right angles to the rod, said loop encircling said longitudinal rod and thereby forming a line of hinges whereby one portion of the mat may be folded back upon the other portion, the relative movement being approximately 180°.

3. A road reinforcing mat in which each unit comprises two series of rods attached at right angles to form a reticular structure, and having the units hinged together, the hinge being formed by a rod of one unit serving as a pivotal axis, and means constituting the body of the hinge being formed by terminal ends of rods of the other unit, said terminal ends each being bent in a helical turn at right angles to the rod of which it forms the terminus, the inside diameter of the turn permitting free turning on said pivotal rod and the pitch of the helix being slightly greater than the diameter of the pivotal rod.

4. A mat for roadway reinforcement comprising two units, each comprising two series of rods attached to each other at right angles, said units being hinged together so that there may be a 180° relative movement, the hinge action being accomplished by means of an axis formed by a rod of one unit and a hook end on a rod of the other unit, said hook end consisting of approximately a 360° spiral turn at right angles to the rod of which it forms the terminus and with an inside diameter permitting free turning movement upon said axis rod, and the pitch of the spiral slightly greater than its inside diameter.

5. A hinged reinforcing mat in which each of the two units comprising same is made up of two series of rods attached at right angles to form a reticular structure, and having the units hinged together, the hinge being formed by a rod of one unit serving as a pivotal axis, about which spiral ends turned at right angles to form the adjacent termini of the rods of the other unit are placed so that there may be a relative movement of 180° between the two units, but from which

axis rod the spiral ends may not become disengaged except by removing the fastening means which hold the rods in right angled position in the structure.

5. 6. The method of making a reinforcing mat from a plurality of units, one of which is provided with a pivot member, comprising the steps of assembling a series of rods in hinged relation to said pivot member by placing separated rods on the pivot member rotating the rods about their respective longitudinal axes, rotating the rods about a point on the pivot member in the direction of the longitudinal axis of the pivot member and then locking the rods together in hinged relation by means of cross rods.

7. The method of making a reinforcing mat from a plurality of units, one of which is provided with a pivot member and rods of an adjacent unit having right angled helical loops, comprising the steps of assembling the series of rods having loops at their respective ends in hinged relation to said pivot member by separately placing the helical loops of said rods angularly over the pivot member rotating the rods through an arc until they are brought to a stop in hinged relation to said pivot member and then locking the rods together in the hinged position by means of cross rods.
